UNITED STATES PATENT OFFICE.

ROY A. McMULLIN, OF BOSTON, MASSACHUSETTS, ASSIGNOR TO STEPHENS-ADAMSON MNFG. CO., A CORPORATION OF ILLINOIS.

COAL BUNKER.

Application filed April 15, 1925. Serial No. 23,417.

To all whom it may concern:

Be it known that I, Roy A. McMULLIN, a citizen of the United States, and resident of Boston, county of Suffolk, and State of 5 Massachusetts, have invented certain new and useful Improvements in Coal Bunkers, of which the following is a specification, and which are illustrated in the accompanying drawings, forming a part thereof.

10 In modern power plants, including a battery of boilers, it has become customary to store the coal in elevated bunkers having discharge spouts, from which the coal is delivered into conveyances, usually called 15 weigh lorries, which in turn deliver the coal to hoppers from which it passes to the boiler furnaces. The coal is either delivered wet or is sprinkled to lay dust, and in consequence water collects in the 20 spouts and has heretofore dripped to the floor of the boiler room, because the gates closing the spouts are not water tight. The principal object of this invention is to dispose of this accumulation of water.

25 In the accompanying drawings,

Fig. 1 is a fragmentary side elevation of a power plant including a battery of furnaces, an overhead bunker, etc.;

Fig. 2 is a fragmentary elevation from 30 a plane indicated by the line 2—2 of Fig. 1;

Fig. 3 is a side elevation of the upper portion of a weigh-lorry and a spout showing the parts in the position they assume just before the lorry begins to open the 35 spout;

Fig. 4 is a similar view showing the parts in an intermediate position;

Fig. 5 is a similar view showing the position they assume when the spout is fully 40 open; and

Fig. 6 is a sectional view taken on the line 6—6 of Fig. 2.

10 indicates a battery of furnaces including hoppers 11 and grates 12. 13 is an 45 overhead coal bunker equipped with a plurality of spouts 14. 15 is a track for the weigh-lorries. In a conventional form these weigh-lorries include a frame 16, carrying a hopper body 17, having a downwardly 50 and laterally inclined spout 18 for delivering the coal to the hoppers 11.

A number of different kinds of spout gates are in use, and the one here illustrated is commonly referred to as the duplex gate.

It includes two curved sections 19 and 20, 55 having rabbetted faces to form the overlapping joint 21 where they come together at about the middle of the spout. Each section is carried by two arms 22, having hubs 23 journaled on pins 24 at the sides 60 of the spouts. The hubs are equipped with meshing teeth 25, by which the gate sections are made to move simultaneously in opening or closing the spout. Weights 26, 65 carried by arms 27, tend to close the gate sections and hold them in closed position.

According to this invention a drip pan is normally located beneath the joints 21 and equipped with means for conducting the accumulated water away to a suitable place 70 of disposal. Preferably these pans 28 are of inverted V-shape form, as indicated in Fig. 6, and have their bottoms inclined to one side, as best shown in Fig. 2. The walls 29 and 30 close the ends of the V-shaped 75 pans. The wall 29 is provided with a threaded boss 31, which receives a suitable length of tubing 32 extending laterally and delivering to a gutter 33, which in turn 80 delivers to a down spout 34 leading to a suitable place of disposal.

The pans are equipped with arms 35 and 36, having hubs 37 and 38 journaled on pins 39 located centrally with respect to the spouts 14. This rotatable mounting of the 85 drip pans permits them to be readily moved clear of the spouts to allow delivery of the coal. Lost motion connection is provided between the pans and the gates, so that the initial movement of the pan toward clear 90 position does not affect the gate, but after the edge of the pan has cleared the joint 21 further movement of the pan requires like movement of the gates toward open 95 position. This lost motion connection may take a variety of forms.

In the preferred construction here illustrated, the arms 35 and 36 are provided with curved slots 40 and 41, which freely receive pins 42 and 43 carried by the gate sections 19 and 20. The slots, however, terminate in shoulders 44, which limit the relative movement between the pan and gate members in one direction. The shoulder 44 on the arm 36 is in a position reverse to that of the shoulder on the arm 35. In this way the gate may be rotated to the right in Fig. 5, and the shoulder 44, cooperating with the

pin 43, will serve to open the gate while the pin 42 merely moves idly through the slot 40. In like manner the pan may be rotated to the left in Fig. 5, and the pin 42, 5 co-operating with the corresponding shoulder 44, will effect an opening of the gate while the pin 43 moves idly through the slot 41.

The weigh lorry is equipped with a contact arm 45, for swinging the pan as the 10 lorry comes into position to receive coal from the particular chute. This arm is mounted on a rotatable shaft 46, having weighted arms 47 and a chain and counter-weight 48, by which it is held in either position 15 to make the arm 45 operative or inoperative, as desired. The pans 28 are equipped with contact rollers 49 and 50 for cooperation with the arm 45.

When the operator desires to take coal 20 from a particular spout he moves the weigh lorry in proper alignment with the spout. As the lorry approaches this position the arm 45 comes in contact with one of the rollers 49 or 50, depending on the direction 25 from which the approach is made. As shown in Fig. 3, it contacts with the roller 49. Further movement to the right from the position shown will bring the parts to the relation shown in Fig. 4, in which the 30 edge of the pan 28 is just clearing the joint 21 between the gate sections, and the pin 43 is about to engage the shoulder 44 and tie the gate section 20 to the pan 28 during any further movement to the right, by which the 35 parts are brought to the relation shown in Fig. 5. Further movement to the right takes the arm 45 beyond the roller 49 and permits the gates to drop to closed position and the pan to assume its normal position beneath 40 the joint 21 for catching the drip. The approach from the left produces a similar operation.

Spouts equipped with pans according to 45 this invention may be operated as conveniently as those now in use, and at the same time all the dirty water collecting in the spouts is caught by the pans and passed on through the tubes 32, the gutters 33 and down spouts 34, to a suitable basement disposal without any attention on the part of 50 the power plant organization.

In order to make the disclosure full and clear I have shown and illustrated a specific construction which I now prefer, but I do 55 not intend thereby to limit the claims or to require an interpretation of them that will permit the substance of the invention to be appropriated without infringement.

I claim as my invention—

60 1. In a device of the class described, the combination of a spout, a gate including two pivotally mounted sections connected to rotate simultaneously in opening and closing the spout, a pivotally mounted drip pan 65 extending beneath the gate, and a lost mo-

tion connection between the drip pan and each of the gate sections.

2. In a device of the class described, the combination of a spout, a lorry adapted to travel beneath said spout, a gate for opening and closing the spout, a laterally movable drip pan extending beneath the gate, a lost motion connection between the drip pan and the gate, and means carried by the lorry for engaging with the drip pan. 70 75

3. In a device of the class described, the combination of a spout, a gate including two sections connected to swing together to close the spout and to swing apart to open the spout, a drip pan extending beneath the juncture of the gate sections, arms carrying the drip pan and pivoted centrally with respect to the spout, and a lost motion connection between the drip pan and the gate. 80

4. In a device of the class described, the combination of a spout, a gate including pivoted sections connected to swing apart to open the spout and to swing together to close the spout, a drip pan extending beneath the joint between said gate sections 90 and mounted to swing aside to clear the spout, and a lost motion connection permitting limited movement of the drip pan with respect to the gate and requiring one section of the gate to move with the drip pan 95 beyond that limit.

5. In a device of the class described, the combination of a spout, a gate including sections adapted to move in opposite directions to open and close the spout, a drip pan extending beneath the juncture of the gate sections and adapted to move laterally to clear the spout, and a lost motion connection between the drip pan and one of said 100 gate sections. 105

6. In a device of the class described, the combination of a spout, a gate closing the spout, a drip pan extending beneath the gate, and a lost motion connection between the gate and the spout. 110

7. In a device of the class described, the combination of a spout, a gate closing the spout, a drip pan extending beneath the gate, a lost motion connection between the gate and the spout, a discharge for the drip pan, and means for receiving water from the discharge. 115

8. In a device of the class described, the combination of a spout, a gate for the spout, means for mounting the gate to permit it to swing to closed and open positions, a drip pan beneath the gate, means for mounting the drip pan permitting it to move from a normal position beneath the gate to a lateral position clear of the spout, and a lost motion connection between the pan and the gate. 120 125

In testimony whereof I affix my signature.

ROY A. McMULLIN.
